WINDOW STRUCTURE

Vernon M. Frey, East Moline, Ill.

Application March 15, 1935, Serial No. 11,345

2 Claims. (Cl. 20—50)

My invention relates generally to window structure, and particularly to an arrangement of a window frame in which a pair of vertically slideable sashes is mounted, the said sashes being in 5 a certain position each swingable on a vertical axis, and an important object of my invention is to provide a window structure of the character indicated which is simple, inexpensive, and which looks like an ordinary window structure.

Another important object of my invention is to provide a window structure of the character indicated above which enables the housewife to easily and safely clean both the inside and the outside of the window sashes, and which will enable 10 eliminating a great part of the danger and expense incident to the cleaning of windows in tall office and other buildings.

Another important object of my invention is to eliminate two pulleys, and the corresponding two sash-cords, and two weights in a window structure, without detracting from the efficiency thereof.

Other important objects of my invention will be apparent from a reading of the following description in connection with the drawings, wherein for purposes of illustration I have shown a preferred embodiment of my invention.

In the drawings:—

Figure 1 is an elevational view of the inner side 30 of an embodiment of the present invention.

Figure 2 is a horizontal sectional view taken through Figure 1 just above the lower sash.

Figure 3 is a horizontal sectional view taken through Figure 1 with both of the sashes lowered 35 and swung inwardly, the sashes being shown in top plan.

Figure 4 is a longitudinal vertical sectional view taken through Figure 1 and showing the window frame in section and one of the stops with a 40 removable section located at the right hand side of the frame.

Figure 5 is a perspective view of the lower part 45 of a stationary section of one of the sectional stops at the right side of the window frame.

Figure 6 is a perspective view of one of the removable sections of the sectional stops.

Figure 7 is an elevational view of the outer side 50 of the window frame showing the spring catches engaged with the detents on the removable sections of the right hand window frame stops.

Figure 8 is a transverse vertical sectional view through one of the catches.

Figure 9 is a perspective view of one of the 55 catches.

Figure 10 is an edge elevational view of the upper part of the lower sash.

Figure 11 is a horizontal cross sectional view taken through the upper part of Figure 11 below the top thereof and showing how an end of the 5 sash-cord is engaged with the keyhole-shaped slot in the slide plate and sash strip.

Figure 12 is a perspective view of the upper part of the slide plate.

Referring in detail to the drawings the numeral 10 5 refers generally to a window structure in accordance with the present invention which includes the window frame 6 which has the left hand side 7 and the right hand side 8. Working in the window frame is the outer sash 9 and 15 the inner sash 10, which sashes, when horizontally aligned in a certain partly open position can be swung inwardly either singly or together to bring the outer side of the sashes within the room in which the window is, so that the outsides as well 20 as the inner sides of the sashes may be washed or otherwise treated without exposing the person within or leaning out of the window structure.

Attached to the inner face of the window frame side 7 is the outer stop 11, the middle stop 12, 25 and the inner stop 13. The facing edges of the stops are grooved as indicated by the numeral 14 to provide confining channels for the slide plates 15 and 16 of the outer sash 9 and the inner sash 10, respectively. The side edges of the slide 30 plates 15 and 16 are slidably confined in the grooves 14, and these slide plates are connected to respective sash strips 17 and 18 whose side edges are slidably engaged with the facing edges of the corresponding stops 11, 12, and 13, as clearly 35 shown in Figure 2.

The opposite edges of the sash work between 40 sectional stops 19, 20, and 21.

The upper end of each slide plate has an inverted keyhole slot 22 opening through the upper 45 end thereof and this keyhole slot is registered with a conforming opening 23 in the outer side of the corresponding sash strip 18 to provide for reception of the lower end provided with a knot or the like enlargement of the sash-cord 24 50 whereby to connect the sash-cord operatively with the corresponding sash. The slide plates extend the full height of the corresponding sashes and are secured thereto by suitable means such as screws 25. The sash strips are preferably of wood 55 in a wooden sash construction, but when the window structure is formed of metal or other suitable material, the entire construction including the sashes and the sash strips may likewise be of metal.

The inner sash 9 has fastened at two or more vertically spaced points on the left hand edge thereof a hinge leaf 26 which is of the same width as the sash and is pivoted as indicated at 27 to a corresponding edge of a correspondingly wide hinge leaf 28 which is fastened to the sash strip 17 and has an anchoring indentation 29, clearly shown in Figure 2. Hinges 30 and 31 of the type just described are provided on the outer sash 9.

The inner sash 10 is provided with broadly similar hinges 32 and 33 which are similarly fastened to the left hand edge of the inner sash 10 and the corresponding sash strip 18 as shown in Figure 2. The hinge structures 32 and 33 are not of the same width as the sash 10 but are wider so that the pivot 34 is inwardly displaced from the inner side of the inner sash, so that when swung inwardly the inner sash will give sufficient clearance for the inward swinging of the outer sash 9 as indicated in Figure 3. It is obvious that an extension 35 on the upper end of the inner sash is provided to bridge the space between the sashes which is caused by the presence of the stops 12 and 20, so as to make the engagement of the sashes weather-proof. It is desired to remark at this point that with the proper placing of ordinary weather-stripping or felt, the present window structure is even more weather-proof and less liable to rattling during storms, than the ordinary window sash arrangements.

The right hand stops 20 and 21 are the sectional stops and each is composed of an upper stationary section 36, a lower stationary section 37, and a removable section 38, the fixed sections 36 and 37 being fastened in any suitable manner to the inner face of the right hand window frame 8.

The upper fixed sections 36 are outwardly and downwardly beveled as indicated at 39 and provided with a squared notch 40, these parts receiving in abutment the angulated portions 41 and the squared tongues 42 on the upper ends of the removable sections 38.

The lower fixed section 37 is upwardly and inwardly beveled and provided with the squared tongue 44 to abut the angulated portions 45 and the squared notch 46 on the lower ends of the removable sections, so that the removable sections must be placed into position by first engaging the lower ends thereof with the described formations on the fixed section 37 and then by an outward swinging movement engaging the formations described on the upper ends of the removable sections with the corresponding formations of the upper fixed sections 36.

The outer side of the upper part of each removable section carries a flush plate 47 which is secured by screws or the like 48 and has formed thereon the detent 49 which is provided with the horizontal working face 50 which terminates at its inner end in a groove 51, and the upwardly and inwardly angulated base 52 which terminates at its upper end in the groove 51. Each of the detents 49 is arranged to pass through an opening 53 in the window frame side 8 and also through an opening 54 in a latch plate 55. Below the opening 54 in each latch plate is a horizontally spaced pair of ears 56 which support a horizontal pivot 57 on which are journaled the lugs 58 on a J-shaped flat spring 59 which has its upper end inwardly pointed through the opening 54 as shown in Figure 9 and again in Figure 4. A spring 59 circumscribed on the pivot 57 is arranged to push the upper end of the spring 59

in the left hand direction. Because of these arrangements and the relative positioning of the detents and the latches, the pushing of the upper part of the movable section 38 into position will cause the detent to engage and hold the upper end of the corresponding spring 59 in such a way as to depress the spring 59 in a downward and outward direction until the groove 51 is reached by the upper end of the said spring, when the resiliency of the said spring assisted by the coiled spring 59 will cause a reverse movement on the part of the spring 59 so that the upper end of the spring 59 will engage in the groove 51 with a positive action, so as to securely lock the movable section in place. Exerting a quick pull in the left hand direction will snap the detent out of holding engagement with the spring 59 and enable removal of the corresponding removable section 38. The arrangements just described apply equally to the sectional stops 20 and 21.

When it is desired to clean the outer side of the sashes, the sashes are brought to such a position that their upper and lower edges come within the upper and lower ends of the removable sections 38. The sections are then removed as indicated, whereupon the right hand edge of the sashes may be swung through the opening resulting from the removal of the sections to such inwardly swung positions as are indicated in Figure 3. A simple reversal of the operations described will enable restoring the sashes to their ordinary vertically slidable positions.

Although I have shown and described herein a preferred embodiment of my invention, it is to be definitely understood that I do not desire to limit the application of the invention thereto, and any change or changes may be made in the materials and in the structure and arrangement of the parts, within the spirit of the invention and the scope of the subjoined claims.

What is claimed is:

1. In combination, an ordinary window frame, three spaced stationary sash stops fastened to one side of said frame and defining two sash receiving channels therebetween, three opposite sash stops secured on the opposite side of said frame and defining two sash receiving channels therebetween, said opposite sash stops including an outer stationary sash stop and two inner sectional sash stops, each sectional sash stop including upper and lower stationary sections and an intermediate removable section, and two sashes slidably mounted channels defined by the said opposite sash stops, the upper and lower ends of said removable sections being upwardly and inwardly inclined and dovetailed with the lower and upper ends respectively of the said upper and lower stationary sections, whereby said removable sections can be removed from the stationary sections only by moving said removable sections inwardly and upwardly toward the opposite side of the window frame, said removable sections including detents extending laterally therefrom and through openings in the respective laterally inward side of the window frame engaged by the removable sections when in place, and spring catches located in said openings with which said detents are removably engageable to hold the removable sections in place.

2. In a window structure including a window frame having a pair of sash stops defining a sash receiving channel therebetween, a sash strip slidably confined in said channel, with its laterally inward face flush with the laterally inward faces of the sash stops, a hinge having a first leaf

fastened to the said laterally inward face of said sash strip, a second hinge leaf pivoted at its inner end to the inner end of the first leaf, said second leaf being fastened to the edge of the sash whereby said sash may be swung inwardly relative to said sash strip and the window frame, said first leaf having a transverse indentation therein containing a compressible sealing element

projecting outwardly therefrom, said sealing element being arranged to be engaged and compressed by a portion of said second hinge leaf into weather-sealing relation between said sash strip and the sash when the sash is in closed 5 position.

VERNON M. FREY.
